OF WASHINGTON.

TAPE MOISTENING AND DELIVERY APPARATUS.

1,383,999.

Specification of Letters Patent. Patented July 5, 1921.

Application filed May 29, 1920. Serial No. 385,211.

To all whom it may concern:

Be it known that we, WILLIAM D. ROBERTSON and STANLEY SAVAGE, citizens of the United States and Great Britain, respectively, residing at Seattle, in the county of King and State of Washington, have invented certain new and useful Improvements in Tape Moistening and Delivery Apparatus, of which the following is a specification.

10 This invention relates to an improvement in tape moistening and delivery apparatus wherein a paper tape or the like may have the adhesive covered surface thereof moistened and delivered for convenient use in 15 sealing package wrappers in the usual manner.

As heretofore constructed machines of this type deliver the tape with the forward end thereof unmoistened, due to the fact that 20 the delivery means and moistening means operate uniformly, and the moistening means is compelled to make a partial movement before delivering moistening fluid to the tape. The present invention overcomes this 25 difficulty by compelling a predetermined action of the moistening means before initial action of the delivery means, so that the full length of tape delivered is properly moistened.

30 The invention is illustrated in the accompanying drawings:—

Figure 1 is a plan of the improved apparatus.

Fig. 2 is a longitudinal central section, 35 partly in elevation of the same.

Fig. 3 is a detail in elevation, illustrating the operating means for the moistening and delivery rolls.

Fig. 4 is a similar view showing the 40 actuator for the operating means.

The improved apparatus comprises a box-like receptacle 1 having a bottom 2, side walls 3, and an end wall 4 of less height than the side walls. At the end of the receptacle remote from the wall 4 is a cylindrical casing 5 within which on a shaft 6 is supported a reel 7 having a supply of tape 8, preferably paper of a comparatively narrow width. Within the receptacle in advance of the reel 7 is a delivery roll 9 having a friction surface 10, as of sand paper or the like, the roll being mounted upon shaft 11 supported in the side walls 3. Pivotally supported in the side walls 3 at 12

are arms 13 connected by a cross piece 14, 55 said arms and cross piece forming a frame carrying idle rollers 15 and 16, the former of which overlies and is adapted to coöperate with the roll 9 for delivery purposes, while the latter guides the tape from the 60 reel to the delivery roll. A spring strip 17 secured to one of the side walls 3 is adapted to bear on the cross bar 14, to secure the desired pressure.

A liquid container 18 is removably supported upon studs 19 projecting from the side walls 3 of the box 1, said receptacle or container 18 being positioned over the end wall 4. A moistening roll 20 is mounted so as to rotate within the container 18, being 65 supported upon shaft 21 mounted in the side walls 3. The surface of the roller 20 is preferably of non-rusting metal though any appropriate material may be used. The surface of the roller 20 is preferably formed 70 with a slot or groove 23 in which operates the free end of a finger 22 secured to the receptacle 1 to prevent the moistened tape from adhering to the surface of the roller.

An important feature of the present invention resides in the operation of the feed roll 9 and the moistening roll 20 by means of a single actuator, the operating means compelling substantially a complete revolution of the moistening roll before the feed 85 or delivery roll is actuated, in order that the initial end of the tape being delivered may be properly moistened. An operating slide 24 is guided in a recess 25 formed in one

side wall 3 of the receptacle 1, said slide 90 having elongated openings 26 and 27 to slidably embrace pinions 28 and 29 secured on the ends of the shafts 11 and 21 respectively. Pinion 29 on the moistening roll is smaller than pinion 28 on the delivery roll, 95 and the openings in the slide correspond in dimensions. The upper walls of the respective openings 26, 27, are formed to provide gear racks 30, 31 adapted to coöperate with the respective pinions in the longitudinal 100 movement of the slide, the rack 31 engaging the pinion 29 before the rack 30 engages the pinion 28. An actuator in the form of a hand lever 32 is pivotally supported at 33 and provided with a lateral pin 34 to 105 enter an inclined slot 35 in the slide 24. A leaf spring 36 in said slot 35 normally holds the slide elevated, so that the racks

will not engage the pinions, as for example in the rearward movement of the slide. As the actuator is depressed the slide is moved forward, the moistening roll given 5 substantially a complete revolution before the delivery roll is operated, so that the tape 8 when reaching the moistening roll bears upon an already moistened surface of said roll.

10 Spaced strips 37, 38, are arranged between the delivery and moistening rolls, being secured to the sides 3 of the receptacle 1, the tape being adapted to pass over the strip 37 and under the strip 38. The forward edge 15 of the strip 38 is serrated at 39 to provide a tearing edge for the tape.

The operation of the apparatus is apparent from the above description, it being obvious that any desired length of tape may 20 be fed from the reel 7 by suitable successive operations of the actuator, and that the entire length of tape so delivered will be effectively moistened. As is usual in this type 25 of machine the tape employed is of the character having a surface supplied with an adhesive, which is effective as such when moistened with water. The container 18 will of course contain water for moistening the adhesive covered side of the tape.

30 What we claim is:—

1. In a moistening apparatus for tape and the like, a supply reel for the tape, a delivery roll by which the tape is fed, a moistening roll for applying moisture to one surface of 35 the tape, and means for operating said rolls to insure a predetermined movement of the moistening roll prior to any movement of the delivery roll, whereby said predetermined movement of the moistening roll 40 causes a moistened surface of the roll to be presented to the tape, so that the entire length of tape delivered is moistened.

2. In a moistening apparatus for tape and the like, a supply reel for the tape, a delivery roll by which the tape is fed, a moistening roll for applying moisture to one surface of the tape, a means for actuating said rolls at different speeds, said means compelling a predetermined movement of the moistening roll prior to any movement of the delivery roll.

3. In a moistening apparatus for tape and the like, a supply reel for the tape, a delivery roll by which the tape is fed, a moistening roll for applying moisture to one surface of the tape, operating pinions for the respective rolls, a slide bar having racks to engage the respective pinions, said racks engaging the pinions at different times, and 60 means for operating the slide.

4. In a moistening apparatus for tape and the like, a supply reel for the tape, a delivery roll by which the tape is fed, a moistening roll for applying moisture to one surface 65 of the tape, an operating pinion for each of

said rolls, the pinion for the moistening roll being smaller than the pinion for the delivery roll, a slide having rack bars to engage said pinions, the rack bar for the moistening roll pinion engaging said pinion prior to the engagement of the remaining rack bar with the delivery roll pinion, and means for operating the slide.

5. In a moistening apparatus for tape and the like, a supply reel for the tape, a delivery roll by which the tape is fed, a moistening roll for applying moisture to one surface of the tape, means for operating said rolls to insure a predetermined movement of the moistening roll prior to any movement of the delivery roll, a frame supported above the delivery roll, an idler carried by said frame to bear on the tape on said delivery roll, and a tape guiding idler carried by said frame.

6. A moistening and delivery apparatus for tape comprising a casing, a supply reel for the tape rotatably mounted therein, a delivery roll having a friction surface rotatable in said casing, a tank mounted in the casing for containing a moistening fluid, a moistening roll rotatable in the casing above and having a portion thereof extending into the tank, a frame pivoted to the upper edge of the casing above the delivery roll, idler rollers for guiding the tape mounted in the frame, one of said rollers bearing on the tape on said delivery roll, pinions connected with the delivery and moistening roll, a slide having racks to engage said pinions, the rack for engaging the moistening roll pinion engaging said pinion before the engagement of the other rack with the delivery roll pinion, and a lever for operating said slide.

7. A tape moistening and delivery apparatus comprising a casing, a supply reel for the tape rotatable in the casing, a delivery roll rotatable in the casing, a container for holding a moistening fluid mounted in the casing, a moistening roll carried by the casing and adapted to rotate in the fluid for moistening the tape, means for holding the tape in engagement with the delivery roll, pinions carried by the rolls, a slide having racks to engage said pinions, the rack for engaging the pinion on the moistening roll engaging said pinion before the engagement of the other rack with the pinion on the delivery roll, said slide having an inclined slot, and an actuator having a projection extending in the slot in said slide for operating the slide.

8. A tape moistening and delivery apparatus comprising a casing, a supply reel for the tape carried thereby, a delivery roll mounted in the casing, a moistening roll rotatable in the casing, said moistening roll having an annular groove formed therein, a finger carried by the casing having its

free end riding in said groove for preventing the adherence of the tape to the moistening roll, a container for supplying moistening fluid to the moistening roll, pinions carried by the rolls, a slide having racks adapted to engage the pinions of the rolls successively to produce a movement of the moistening roll prior to a movement of the delivery roll, and means for operating the slide.

9. A tape moistening and delivery apparatus comprising a casing, a supply reel for the tape mounted therein, a delivery roll rotatable in the casing, a moistening roll 15 rotatable in the casing, said moistening roll having a groove formed therein, a finger operating in the groove to prevent the tape adhering to the roll, and means for rotating the rolls to produce a predetermined movement of the moistening before the movement 20 of the delivery roll.

10. A tape moistening end delivery apparatus comprising a supply reel for the tape, a delivery roll by which the tape is fed, a

moistening roll for applying moisture to one 25 surface of the tape, a container for moistening liquid in which said moistening roll is adapted to rotate in contact with the liquid, and means for operating said rolls to insure a predetermined movement of the moistening roll prior to any movement of the delivery roll.

11. A tape moistening and delivery apparatus comprising a supply reel for the tape, a delivery roll by which the tape is fed, a 35 container for moistening fluid, a moistening roll adapted to rotate in the container, means for preventing the tape from adhering to the moistening roll, and means for operating the rolls, said means compelling 40 a predetermined movement of the moistening roll before the movement of the other roll.

In testimony whereof we affix our signature.

WILLIAM D. ROBERTSON.
STANLEY SAVAGE.
